UNITED STATES PATENT OFFICE.

ALBERT H. KELLY, OF SALT LAKE CITY, UTAH.

BILL-FILE.

No. 926,257.

Specification of Letters Patent.

Patented June 29, 1909.

Application filed July 14, 1908. Serial No. 443,552.

To all whom it may concern:

Be it known that I, ALBERT H. KELLY, a citizen of the United States, residing at Salt Lake City, in the county of Salt Lake and State of Utah, have invented certain new and useful Improvements in Bill-Files, of which the following is a specification.

The purpose of my invention is to provide a bill file that will allow a bill placed therein to be shifted from its position as filed, to another herein referred to as the posting position; and to also provide a lock for said file, so that a bill can not be filed thereon, or its relative position changed as to other bills, without unlocking the file. These objects I attain by my invention that is illustrated by the accompanying drawings, in which similar figures of reference indicate like parts.

20 Figure 1 is an isometric view. Fig. 2 is a section on line x, x , of Fig. 1. Fig. 3 is a plan view. Fig. 4 is a plan of the bottom of the post base, showing the locking parts. Fig. 5 is a section of the inter-locking of the 25 posts. Fig. 6 is a section of the lower portion of the movable posts.

The base 1, is made of any light material such as wood, papier mâché, or metal; a portion of the central part 2, is cut away to 30 receive the locking parts, and from this cut 2 to one end or edge is provided a ferruled hole 3, within which is placed the shifting staff 4, of the lock. Covering cut 2, is provided a post base 5, that is secured to the 35 base 1, by screws 6. To this base 5, and near the corners thereof are perpendicularly and rigidly attached two posts 7, the upper ends of which have a centrally located hole 8. Within the other corners of the post base 40 5, are fitted the axially and vertically movable posts 9, that are so fitted in the base 5, that they have unlimited axial motion but a limited vertical motion, and are provided near the bottom with a circumferential cut 45 or channel 10. The upper portion of said posts 9 are bent, preferably in a curve, and the ends reduced so that they may be inserted in the holes 8, of the posts 7. The curved parts of posts 9 are flattened vertically at 11, so that the flattened parts have the thickness and edge of a table knife, the purpose of which will be more fully explained hereinafter.

On the under side of the post base 5 is 55 secured, by the pivot 12, the pivoted spring latch 13, to one end of which is attached

the shifting staff 4. As a brace and stay for the bottom of the rigid posts 7, and secured to the post base 5 is a bar 16, and secured thereto and between it and the pivoted spring latch 13, is a spring 15, which keeps the parts of pivoted spring latch 13, within the cut or channel 10, of the posts 9 when so desired, and thus prevents any vertical motion while so situated. When the 60 reduced ends of posts 9 are inserted in the holes 8 of the rigid posts 7, the locking of the posts 9 securely locks the file. The end of the shifting staff 4 is threaded. The key 14 has an enlarged section 19 at one end, 70 and an inner axially located threaded hole therethrough, extending into the key 14.

The bill, paper or sheet 17, has cut or punched near one edge two holes 20 of sufficient size to receive freely, the posts. And 75 about one inch away, and parallel to the edge of the paper is cut or punched two similar holes 18, each set of holes being connected by a slit or shear cut from hole 18 to hole 20. 80

To unlock the file and place bills thereon, the key 14 is inserted into the ferruled hole 3, the threads within the end of the key 14 engage the threads on the end of the shifting staff 4, and a few turns of the key will 85 cause the enlarged section 19, of the key 14 to come in contact with the ferrule of the hole 3. Then the continuation of the turning of the key will draw the shifting staff 90 laterally and the edge of the pivoted spring latch 13 will be drawn out of the channel 10 of the posts 9, and flex the spring 15, releasing the posts 9 so that they can be moved enough vertically and axially, so that the reduced ends of the posts 9 can be removed 95 from the holes 8. The paper 17, can then be placed on the posts 7 by slipping the holes 18 in the paper, over the posts 7, thus giving the filing position. When the desired number of sheets or bills have been 100 placed on the file, the reduced ends of the posts 9 are inserted into the holes 8 of the posts 7, and the key 14 is removed from the shifting staff 4; the tension of the spring 15 105 causes the edge of the pivoted spring latch 13 to enter the cut or channel 10 of the posts 9, and securely locks the file. The sheets or bills can be shifted from the position as filed in holes 18 to the posting position by 110 raising the sheets or bills to the flattened part 11 of the posts 9, where the knife edged part allows the shifting from hole 18 to hole

20, without injury to the paper. The sheets or bills can be used on posts 9 as shown in Fig. 1 or on posts 7. The tension of the spring 15 keeps the file locked until unlocked by its particular key. The size of the ferruled hole, the cut of the threads on the shifting staff and the key, and their relative lengths can be used to vary the lock.

Having thus described my invention I desire to secure by Letters Patent—

1. In a bill file the combination of, two posts having a centrally located hole in the top of each post and secured to a base, with two axially and vertically movable posts adjustably secured to said base, and having their upper portions curved and flattened and whose upper ends are reduced to enter the hole in the top of the first mentioned posts, and a spring, a pivoted spring latch attached to one end of said spring, a threaded shifting staff secured to said pivoted spring latch, and an axially inner threaded key, whose threads mesh with the threads on said shifting staff.

2. In a bill file, the combination of a sheet of paper having two sets of holes, each set connected by a slit, and two axially and vertically movable posts whose upper ends are curved, and a portion of the curve flattened, which posts are adjustably attached to a base, and which posts have a circumferential cut near the bottom, with two posts rigidly secured to said base and whose upper ends are fitted to receive the ends of the first mentioned posts, a pivoted spring latch secured to the under side of said base, a shifting staff, and a spring secured to said spring latch.

3. In a bill file, the combination of a sheet of paper having two holes therethrough, each hole formed by two circular holes connected by a cut, and two axially and vertically movable posts adjustably attached to a base, a cut near the bottom of said posts,

with two posts perpendicularly secured to 45 said base, whose upper ends are fitted to engage with the curved portion of the first mentioned posts, a pivoted spring latch secured to the under side of said base and fitted to engage the cut in the axially and 50 vertically movable posts, a threaded shifting staff attached to said pivoted spring latch, a spring for said latch, and a key with an axially located threaded hole therein.

4. In a bill file consisting of a base, having a ferruled hole therein, a key with an axially located threaded hole therein, a shifting staff threaded to engage the threads of said key, a pivoted latch connected with said shifting staff, a spring attached to said pivoted latch, two axially and vertically movable posts adjustably secured to said base, a circumferential channel near the bottom of said posts, two posts perpendicularly secured to said base whose upper ends are 65 fitted to receive the ends of the first mentioned posts, as and for the purposes described.

5. The combination of a sheet of paper having two holes therethrough, each hole 70 formed by two circular holes connected by a slit, and two axially and vertically movable posts having their upper portions curved, with two posts perpendicularly secured to a base and whose upper ends engage the ends of the first mentioned posts, a pivoted spring latch attached to the under side of said base, a threaded shifting staff attached to said spring latch, a spring for 75 said latch, and a key with an inner threaded hole therein whose threads mesh with the threads on said shifting staff.

In testimony whereof I have affixed my signature in presence of two witnesses.

ALBERT H. KELLY.
